UNITED STATES PATENT OFFICE.

PIERRE JEAN RENÉ POSTEL-VINAY, OF PARIS, FRANCE, ASSIGNOR TO SOCIETE DES MOTEURS SALMSON (SYSTEME CANTON-UNNE), OF PARIS, SEINE, FRANCE.

MAGNETO-FRAME.

1,349,692.

Specification of Letters Patent. Patented Aug. 17, 1920.

Application filed October 13, 1919. Serial No. 330,472.

To all whom it may concern:

Be it known that I, PIERRE JEAN RENÉ POSTEL-VINAY, a citizen of the Republic of France, residing at 46 Boulevard de la Tour-Maubourg, Paris, Seine, in the Republic of France, have invented new and useful Improvements in Magneto-Frames, of which the following is a specification.

Magneto frames are usually provided with a removable part or lid which covers the brush holder used for receiving the current from the armature. According to present practice, such lid is secured upon a plane surface of the frame and centering is obtained by means of the fastening screws only.

This invention has for its object fastening means for securing the lid upon the frame in which the coöperating bearing surfaces of the frame and lid comprise a flat annular surface and a conical surface extending over a certain arc, the lid being fastened to the frame by means of inclined screws so as to insure a proper contact between the said bearing surfaces.

In the annexed drawing given by way of example:

Figure 1 is a vertical section along the line A—B, Fig. 2, of a frame provided with its lid and mounted upon a jig plate used for machining said frame on a lathe.

Fig. 2 is a corresponding plan view.

Fig. 3 is an enlarged sectional view along the line E—F, Fig. 2 showing the coöperating bearing surfaces.

b is the frame of the magneto and c is the removable part or lid thereof, which covers the brush-holder for the armature, not shown. The lid is supported on the frame by two adjacent bearing surfaces comprising a flat arcuated surface shown in section at d f extending over a certain arc g i (Fig. 2) and a conical surface d k extending over the same arc.

45 The lid is secured in position by screws r which are set at an angle so as to take advantage of the thicker portions of the frame and clamp the lid at the same time against the cone shaped and plane bearing

surfaces. The heads of said screws can thus be concealed within the lid, which improves the general appearance of the frame.

The aforesaid bearing surfaces may be easily obtained on a lathe.

In connection with the bearing surfaces on the frames, it will be of advantage to use the jig shown in Figs. 1 and 2 which comprise the plate j provided with an upright portion m having a boss n upon which the frame is centered. The part m has such a reduced width and the radius of the circle o (Fig. 2) corresponding to the bearing surfaces of the frame is sufficiently great so that the tool will clear the opposite end of the frame b as well as the part n of the jig in the turning operation.

It will be seen that by means of the above described arrangement the lid is strongly fixed upon the frame and is perfectly centered, the fastening screws are sufficiently concealed and the parts may be turned out very economically on a lathe.

The invention is not restricted to the details of execution shown or described which have been indicated by way of example only.

Having now described my invention what I claim as new and desire to secure by Letters Patent is:

1. The combination of a magneto frame provided with an arcuated plane bearing surface and an arcuated conical bearing surface, a removable lid having corresponding bearing surfaces adapted to engage the bearing surfaces on the magneto frame respectively, and means for securing the lid to the frame.

2. The combination of a magneto frame provided with an arcuated plane bearing surface and an arcuated conical bearing surface, a removable lid having corresponding bearing surfaces adapted to engage the bearing surfaces on the magneto frame respectively, and inclined fastening screws extending through the lid and screwed into the frame.

3. The combination of a magneto frame provided with an arcuated plane bearing

surface and an arcuated conical bearing surface, a removable lid having corresponding bearing surfaces adapted to engage the bearing surfaces on the magneto frame respectively, and means for securing the lid to the frame, the said arcuated bearing surfaces being formed on such a radius that

the whole of the frame is located within the corresponding circle whereby the bearing surfaces on the frame may be easily 10 machined on a lathe.

In testimony whereof I have signed my name to this specification.

PIERRE JEAN RENÉ POSTEL-VINAY.
